United States Patent Office.

EBERHARD FLUES, OF FORT WASHINGTON, PENNSYLVANIA.

Design No. 3,987, dated April 26, 1870.

DESIGN FOR A SHAWL-MANTLE.

The Schedule referred to in these Letters Patent and making part of the same.

To all whom it may concern:

Be it known that I, EBERHARD FLUES, of Fort Washington, in the county of Montgomery and State of Pennsylvania, have invented and produced a new and original Design for Ladies' Outer Garments, which I style "La Romaine." The following is a specification of the same.

The nature of my design is fully represented in the accompanying drawing to which reference is made, and in which—

Figures 2 and 3, views of detached portions used, making up the design.

The garment which is the subject of this design is intended to be worn, like a mantle, over the shoulders of the person.

It is composed of two pieces, A A, having two parallel edges, b c, and one of their ends at right angles to said edges, but their other end cut sloping, as at a.

The sloping ends a of the two pieces are then sewn together, forming a seam up the back when applied to the person, and the bottom and end-edges may be fringed or ornamented.

A collar, made up of sections B B, of the configuration shown in figs. 1 and 3, is applied to the neck-portion of the garment, as represented, and the garment provided with cords or other fastenings to secure it around the neck of the wearer.

I claim the design for a lady's outer garment, as shown.

EBERHARD FLUES.
